(57) **CLAIM**

The ornamental design for a bench-towel, as shown and described.

DESCRIPTION

FIG. 1 is a perspective view of the bench-towel, showing the new design;

FIG. 2 is a front view of the bench-towel;

FIG. 3 is a back view of the bench-towel;

FIG. 4 is a left side view of the bench-towel;

FIG. 5 is a right side view of the bench-towel;

FIG. 6 is a top view of the bench-towel;

FIG. 7 is a bottom view of the bench-towel; and,

FIG. 8 is a rear perspective view shown in a position of use on an environmental chair.

The dotted lines depicting a bench in FIG. 8 represent environment that forms no part of the claimed design. All other broken lines represent stitching that forms a part of the claim.
